(57) **CLAIM**

The ornamental design for a long-spiked electrode for a stun device, as shown and described.

DESCRIPTION

FIG. 1 is a perspective view of a long-spiked electrode for a stun device, with environmental structure shown in broken lines.

FIG. 2 is a top plan view.

FIG. 3 is a first side elevation view; and,
FIG. 4 is a second side elevation view.

The broken line showing of the environmental structure is for illustrative purposes only and forms no part of the claimed design.
